UNITED STATES PATENT OFFICE.

EDMOND FILLETTAZ, OF NEUILLY-SUR-SEINE, FRANCE.

STARTING MECHANISM FOR EXPLOSION-MOTORS.

1,113,424.

Specification of Letters Patent. Patented Oct. 13, 1914.

Application filed December 12, 1913. Serial No. 806,255.

To all whom it may concern:

Be it known that I, EDMOND FILLETTAZ, a citizen of the French Republic, residing at Neuilly-sur-Seine, in France, have invented a certain new and useful Improvement in Starting Mechanism for Explosion-Motors, of which the following is a specification.

This invention relates to starting mechanism for explosion motors, chiefly applicable for starting the motors of motor cars, boats, aeroplanes, etc.

The mechanism is essentially characterized by the combination of pawl and ratchet free wheel mechanism mounted on a shaft connected with the shaft of the motor and operated from a distance with mechanism automatically producing the disengagement of the starting mechanism should the motor accidentally turn backward.

The invention also comprises various secondary improvements which will be well understood by referring to the annexed drawings in which:—

25 Figure 1 is an elevation of a part of motor-car provided with the improved starting mechanism. Fig. 2 is a plan view of Fig. 1. Fig. 3 is a section and Fig. 4 a side view on a larger scale of the part of the 30 mechanism transmitting to a cable the movement imparted to the operating lever. Figs. 5 and 6 are respectively front and plan views of a guide pulley for the cable and its fixing means. Fig. 7 is an elevation 35 of the interior of the pawl mechanism arranged at the end of the motor shaft. Fig. 8 is a longitudinal section of Fig. 7. Fig. 9 is a section of the pawl mechanism showing the position of the parts produced by a 40 reversal of the motor. Fig. 10 is a section on line $a-a$ of Fig. 8. Fig. 11 is a perspective view of the member which insures the mechanical connection between the engaging and disengaging mechanism in case of 45 reversal of the motor. Fig. 12 is a section on line $b-b$ of Fig. 8 and illustrating the clutch mechanism connecting the shaft of the starting mechanism with the motor shaft.

50 The starting mechanism includes: 1. An operating device arranged on the side bar of the frame and within reach of the driver. 2. A guide pulley for the cable which latter extends from the operating device to the 55 starting mechanism proper. 3. A starting device arranged at the end of the motor

shaft. 4. An automatic disengaging device in case of sudden backward action of the motor.

The operating mechanism arranged on the side bar of the frame on the driving side comprises an operating lever 1 mounted on the axle 2 and acting by means of toothed sectors 3 and 4 on an arm 5 carried by an axle 6 at the end of which arm the cable 7 is fastened. The two sectors 3 and 4 are inclosed in a casing 8 fixed by bolts 9 to the side bar 10. The walls of this casing form bearings for the axles 2 and 6, the former of which is extended outside the frame to bring the operating lever clear of the car body; the axle 6 is extended inside the frame so that the cable may be hidden and protected. The casing 8 has also a tubular extension 11 in which a spring 12 is arranged. The function of this spring is to draw the sector 3 to the suitable position for maintaining the cable 7 stretched. For this purpose the said sector is provided with a pivot 13 on which is articulated a connecting-rod 14 which extends through the spring 12 and has its end screw threaded for the reception of a nut 15 serving as a regulatable abutment for the spring 12. The spring 12 exercises continual traction on the connecting-rod and tends to displace the lever 1 and the arm 5 in the direction indicated by the arrows A and B (Fig. 3). It is completely compressed when the lever 1 is shifted right forward and expands while adding its force to that exerted by the driver when the said lever is shifted back again.

The use of a casing such as 8 provides compactness of the whole and tightness of the various members of the operating device. It protects these members, and especially the sectors 3 and 4 from mud and dust and obviates the defects which would result from the separate mounting of each of the members. Abutments 16 are arranged against which the sector 3 abuts in its extreme positions, and which limit the movement which can be imparted to the lever 1.

The guide pulley 17 over which the cable passes between the arm 5 and the starting mechanism, is arranged in a casing comprising two cheeks 18 connected by a wall 19. The cable 7 passes into the casing through a socket 20 which absolutely prevents its leaving the groove of the pulley; and in order to allow the cable to oscillate, the casing is articulated on a pin 21 carried

by a plate 22 which serves as a support for the pulley, and by means of which it is fixed in position. This plate, which is fixed on the vehicle spring 27 has in its center an elongated slot 23 into which passes a pin 24 arranged on the car axle 28, said pin passing through the springs, the whole being fixed by loops 25 and plates 26 which maintain the springs on the axle. The elongating of the slot 23 allows of regulating the position of the plate 22 so that the cable guiding socket 20 is in the plane of oscillation of the latter. The said cable is attached at its other end to a grooved pulley 29 arranged on the mechanism which drives the motor shaft. This pulley is mounted eccentrically about its axis of rotation and forms a cam, as will now be explained. The hub of this pulley surrounds a sleeve 30 which it drives, in the direction of the motor's rotation, by means of a ball clutch 31. The rotation of this sleeve is transmitted by means of a member 32 to the shaft 33 maintained in extension of the motor shaft 34 by a collar 35 fixed to the cross-bar 36 which forms the front brace of the car frame.

The member 32 surrounding the shaft 33, which it sets in action, also insures its disengagement from the sleeve 30 when a backward movement of the motor drives it backward. This member, the form of which is clearly indicated by Fig. 11, is composed of a cylindrical core having a number of long keys 37 engaged in corresponding grooves 38 of the sleeve 30, the effect of which is to cause the member 32 to assume the rotatory movement of the latter, while allowing it to slide longitudinally with respect to the said sleeve. It has grooves 38 which fit on shoulders 39 carried by the shaft 33 and which, when engaged in them, connect the shaft 33 with the member 32. This connection ceases when the member 32 is moved longitudinally, the grooves 38 abandoning the shoulders 39. The normal position of the member 32 which is the position of engagement with the shoulders 39, is insured by a spring 52 which bears on said member. The member 32 has also on its face turned toward the motor two sloping abutments 40 normally engaged with similar abutments 41 carried by a crown 42. This crown is provided with balls 43 forming clutch members in a cup 44 screwed on the front part of the collar 35. This ball clutch and the thread of the screw which supports the cup 44 allows the crown 42 to turn with the shaft 33 in the direction of the normal rotation of the motor, but fix it in the contrary direction and without being possible for it to unscrew the cup 44. At rest the shaft 33 is clutched to the shaft 34 of the motor by means of the device shown in Figs. 8 and 12, which comprises balls 45 wedging themselves at rest and at the time of starting between the walls

of recesses 46 formed in a sleeve 47 carried by the motor shaft and between other recesses 48 formed in a second sleeve 49 fixed on the shaft 33. The said balls engage in the recesses 46 under the action of the centrifugal force when the motor reaches a certain speed, which unclutches the shaft 33. All this mechanism is protected by a cover 50 screwed on to the hub of the pulley 29 and to which is fixed a ring 51 containing a spiral spring 53, of which one end is fixed to the said ring while the other is fixed to the neck of the fixed cup 44. The function of this spring is to bring back the pulley 29 to its initial position, at the moment of starting, when the lever 1 is pushed forward, and overcomes the action of the spring 12 on the cable 7.

The position of the mechanism at the moment of the starting of the motor is as shown in Figs. 7 and 8. The traction of the cable turns the pulley in the direction of the arrow C (Fig. 7). It is to be observed that by reason of the shape of the pulley, the cable begins to act on a small radius which gradually increases and then diminishes in length. This allows of giving the pulley 29 a relatively high angular speed at the start in order that the suction in the motor cylinders may be free; then the progressive increase of the radius allows the most important part of the compression to be effected without great effort; finally before the end of the compression, the speed of rotation of the sleeve 30 again increases owing to the diminution of the radius of the pulley 29, which facilitates the ignition.

By its rotatory movement the pulley 29 engages the sleeve 30 which, by means of the member 32 drives the shaft 33 which in its turn actuates the motor shaft by means of the ball clutch. Directly the motor starts and after some rotations, the balls 45 are driven by the centrifugal force to the bottom of the recesses 46 and the shafts 33 and 34 are uncoupled. The starting mechanism is thus set free and remains in equilibrium by the antagonistic action of the springs 12 and 53.

If the motor accidentally rotates backward, the shaft 33 is rotated in the same direction before the balls 45 have retired from the recesses 46. The movement of the shaft then actuates the member 32, the inclined abutments of which, acting on those of the fixed crown 42 shift the member 32 along the shaft 33 the said member becoming disengaged from the shoulders 39, and becoming free until the motor stops or until it is engaged by a fresh attempt at starting. In order that a slight recoil movement of the motor may not bring the unclutching mechanism into action, the abutment surfaces of the member 32 and of the crown 42 only take up a small part of the periphery of

these members, so as only to come into action by a reverse movement of certain importance.

What I claim as my invention and desire 5 to secure by Letters Patent of the United States is:—

1. In starting mechanism for explosion motors, the combination of a shaft in axial alinement with the motor shaft, a sleeve 10 surrounding said shaft, a pulley eccentrically mounted on said sleeve, clutch mechanism between said pulley and said sleeve, a cord one end of which is attached to said pulley and adapted to rotate said pulley to cause rotation of said sleeve through said clutch mechanism, by traction on said cord, means for rotating said shaft by the rotation of said sleeve, means allowing rotation of said shaft in one direction without rotating 15 said sleeve, means for clutching said shaft to said motor shaft, and means allowing the release of said last mentioned clutching means when the motor has attained a certain speed.

25 2. In starting mechanism for explosion motors, the combination of a shaft in axial alinement with the motor shaft, a sleeve surrounding said shaft, a pulley eccentrically mounted on said sleeve, clutch mechanism between said pulley and said sleeve, a cord one end of which is attached to said pulley, a lever, means operated by said lever adapted to exert traction on said cord to rotate said pulley to cause rotation of said sleeve through said clutch mechanism, means for rotating said shaft by the rotation of said sleeve, means allowing rotation of said shaft in one direction without rotating said sleeve, means for clutching said shaft to said motor shaft, and means allowing the release of said last mentioned clutching 30 means when the motor has attained a certain speed.

3. In starting mechanism for explosion 45 motors, the combination of a shaft in axial alinement with the motor shaft, a sleeve surrounding said shaft, a pulley eccentrically mounted on said sleeve, clutch mechanism between said pulley and said sleeve, a cord one end of which is attached to said pulley, a hand lever, a toothed sector connected thereto and operated thereby, a second lever having its free end connected to the other end of said cord, a toothed sector 50 connected to said latter lever gearing with the aforesaid sector and operated thereby to swing said latter lever and cause same to exert traction on said cord to rotate said pulley to cause rotation of said sleeve through said clutch mechanism, means for limiting the movement of said hand lever, spring governed means for maintaining said cord stretched, means for rotating said shaft by the rotation of said sleeve, means allowing 55 rotation of said shaft in one direction

without rotating said sleeve, means for clutching said shaft to said motor shaft and means allowing the release of said last mentioned clutching means when the motor has attained a certain speed.

4. In starting mechanism for explosion 70 motors, the combination of a shaft in axial alinement with the motor shaft, a sleeve surrounding said shaft, a pulley eccentrically mounted on said sleeve, clutch mechanism between said pulley and said sleeve, a cord one end of which is attached to said pulley, an operating lever, mechanism for exerting traction on said cord by the operation of said lever to rotate said pulley to cause rotation of said sleeve through said clutch mechanism, a casing inclosing said traction mechanism, means inclosed in said casing for maintaining said cord stretched, a guide pulley for said cord, a 75 pivoted casing inclosing said guide pulley and having an inlet and outlet for said cord, means for attaching said latter casing to the suspension spring of a motor car, means for rotating said shaft by the rotation of 80 said sleeve, means allowing rotation of said shaft in one direction without rotating said sleeve, means for clutching said shaft to said motor shaft, and means allowing the release of said last mentioned clutching 85 means when the motor has attained a certain speed.

5. In starting mechanism for explosion 90 motors, the combination of a shaft in axial alinement with the motor shaft, a sleeve surrounding said shaft, a pulley eccentrically mounted on said sleeve, clutch mechanism between said pulley and said sleeve, a cord one end of which is attached to said pulley and adapted to rotate said 95 pulley by traction on said cord so as to initially cause a maximum angular speed of said pulley which progressively decreases and then again increases to the maximum and causes similar rotation of said sleeve through said clutch mechanism, means for rotating said shaft by the rotation of said sleeve, means allowing rotation of said shaft in one direction without rotating said sleeve, means for clutching said shaft to said motor shaft, and means allowing the release of said last mentioned clutching means when the motor has attained a certain speed.

6. In starting mechanism for explosion 100 motors the combination of a shaft in axial alinement with the motor shaft, a sleeve provided with grooves surrounding said shaft, a pulley eccentrically mounted on said sleeve, means for rotating said pulley, a ball clutch between said pulley and said 105 sleeve allowing said sleeve to be rotated in the direction of rotation of the motor by means of said pulley, a movable member comprising longitudinal internal grooves, within said sleeve mounted on said shaft, 110

115

120

125

130

a collar supporting said shaft, keys on said member engaging in the grooves of said sleeve and allowing it to slide longitudinally with respect to said sleeve, shoulders on said shaft adapted to engage in the internal grooves of said member when said member is in normal position, a spring for holding said member in said position and means operated by reverse rotation of the motor shaft for causing said member to slide longitudinally on said shaft to become disengaged from said shaft.

7. In starting mechanism for explosion motors the combination of a shaft in axial alinement with the motor shaft, a sleeve provided with grooves surrounding said shaft, a pulley eccentrically mounted on said sleeve, means for rotating said pulley, a ball clutch between said pulley and said sleeve allowing said sleeve to be rotated in the direction of rotation of the motor by means of said pulley, a movable member comprising longitudinal internal grooves, within said sleeve mounted on said shaft,

a collar supporting said shaft, keys on said member engaging in the grooves of said sleeve and allowing it to slide longitudinally with respect to said sleeve, shoulders on said shaft adapted to engage in the internal grooves of said member when said member is in normal position, a spring for holding said member in said position, sloping abutments on said member, a crown, sloping abutments thereon co-acting with the abutments of said member, with slight play, clutch mechanism allowing said crown to rotate in the direction of rotation of the motor only and clutch mechanism automatically unclutching said shaft from the motor shaft when the motor has attained a certain speed. 40

In witness whereof I have signed this specification in the presence of two witnesses.

EDMOND FILLETTAZ.
